Primary Examiner — Michael A. Pratt(74) *Attorney, Agent, or Firm* — Mitchell Law PLLC;
Matthew W. Mitchell(57) **CLAIM**

The ornamental design for a silencer tube body, as shown and described.

DESCRIPTION

FIG. 1 is a front isometric view of the silencer tube body of the present invention;

FIG. 2 is a second isometric view thereof;

FIG. 3 is a top plan view thereof;

FIG. 4 is a bottom plan view thereof;

FIG. 5 is a right-side view thereof;

FIG. 6 is a left-side view thereof;

FIG. 7 is a front view thereof; and,

FIG. 8 is a rear view thereof.

The broken lines are for purposes of illustrating portions of the silencer tube body that form no part of the claimed design.

1 Claim, 8 Drawing Sheets(56)
